(57) CLAIM

The ornamental design for a cookware set as shown and described.

DESCRIPTION

FIG. 1 is a front elevational view of a first component of a cookware set, the second and third components omitted for better illustration;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front elevational view of a second component of a cookware set, the first and third components omitted for better illustration;

FIG. 9 is a rear elevational view thereof;

FIG. 10 is a left side view thereof;

FIG. 11 is a right side view thereof;

FIG. 12 is a top plan view thereof;

FIG. 13 is a bottom plan view thereof;

FIG. 14 is a perspective view thereof;

FIG. 15 is a front elevational view of a third component of a cookware set, the first and second components omitted for better illustration;

FIG. 16 is a rear elevational view thereof;

FIG. 17 is a left side view thereof;

FIG. 18 is a right side view thereof;

FIG. 19 is a top plan view thereof;

FIG. 20 is a bottom plan view thereof;

FIG. 21 is a perspective view thereof; and,

FIG. 22 is a perspective view of the entire cookware set.
